UNITED STATES PATENT OFFICE

2,191,725

TORQUE MEASURING WRENCH

Ben Pepperdine, Chicago, Ill.

Application June 23, 1937, Serial No. 149,897

4 Claims. (Cl. 265—1)

The invention relates to improvements in torque measuring wrenches and has for its primary object the provision of an improved wrench of the character indicated which is of simple construction and highly efficient in use.

Another object of the invention is the provision of a wrench of the character indicated which can not get out of adjustment and will therefore be permanently accurate in operation.

Another object of the invention is the provision of a wrench of the character indicated in which the measuring means is readily removable and replaceable.

Another object of the invention is the provision of a wrench of the character indicated which is of compact design and therefore useable efficiently in confined or limited space.

Other objects will appear hereinafter.

The invention consists in the combinations and arrangements of parts hereinafter described and claimed.

The invention will be best understood by reference to the accompanying drawing forming a part hereof and in which:

Fig. 1 is a top plan view of a torque measuring wrench embodying the invention;

Fig. 2 is a side view of the same.

Fig. 3 is an enlarged detailed section taken through a compressible chamber or metallic bellows employed in the construction.

The embodiment of the invention illustrated in the drawing comprises a wrench head 10 of any usual or desired construction and having a socket wrench 11 detachably and operatively connected therewith in the usual way. A wrench arm 12 is operatively connected with the wrench head 10 preferably by means of a usual form of ratchet such, for example as that illustrated in U. S. patent to McGuffey, No. 1,258,582 dated March 5, 1918, and whereby the socket wrench 11 may be readily turned in one direction by means of the wrench arm 12 as will be readily understood by those skilled in the art.

A handle-lever 13 is pivotally mounted on the wrench head 10 and is provided at its free end with a knurled handle 14. At substantially its center the handle-lever 13 is provided with a boss or enlargement 15 having a transverse bore in registration with the end of the wrench arm 12, as indicated. A sealed compressible chamber 16 in the form of a metallic bellows having corrugated sides as shown is soldered or otherwise secured to a bored fitting 17 which has threaded connection at 18 with the bore in the boss 15 and whereby said chamber may be readily removed

and replaced. A contact cap 19 is loosely arranged over the end of the chamber 16 and in the corresponding end of the bore in the boss 15, in position to make operative contact with the contact finger 20 at the operative end of the wrench arm 12, said contact cap serving to protect the end of the chamber 16 from injury or wear. A metallic clip 21 is secured as shown to the wrench arm 12 and loosely embraces the handle lever 13 thereby permitting of limited movement between them so as to facilitate the operation of the wrench arm 12 in manipulating the wrench 11.

A pressure gauge 22 is arranged in sealed communication with the bore of the fitting 17 and chamber 16 through the medium of a threaded nipple 23, said pressure gauge being provided with an indicator arm 24 cooperating with a scale thereon as shown. The pressure chamber 16, bore of the fitting 17, and the interior of the gauge 22 are evacuated of air and completely filled with a liquid permanently sealed to hold heavy pressure and the scale of the gauge 22 is graduated to read in foot pounds.

In use and in operation the wrench 11, carried by the wrench head 10 is engaged with a nut and the handle-lever 13 manipulated to press the contact cap 19 against the contact finger 20 of the wrench arm 12, thereby exerting tightening force or torque on the nut. Obviously the reaction from the force thus exerted will be transmitted to the end of the chamber or bellows 16, thereby compressing the sides thereof and transmitting the pressure of said reaction to the pressure gauge 22 where it will be indicated in foot pounds thereon. In this way the operator may know in foot pounds exactly the torque he is exerting on the wrench and therefore may accurately and uniformly tighten nuts on constructions requiring such careful manipulation thereof. All joints being permanently sealed there is no possibility of leakage and therefore the gauge can not get out of adjustment and will be permanently accurate. There are no moving parts in the construction to wear; the bellows and gauge assembly may be readily removed and replaced if necessary; all detailed graduations and adjustments may be permanently made at the factory; the compactness of design permits of ready use of the wrench in limited space; and the wrench will be found to be durable and highly efficient in use. The specific form and arrangement of parts disclosed is a simple and effective one for the purpose.

While I have illustrated and described the pre-

ferred form of construction for carrying my invention into effect this is capable of variations and modifications without departing from the spirit of the invention.

5 I therefore do not wish to be limited to the precise details disclosed but desire to avail myself of such variations and modifications as fall within the scope of the appended claims.

I claim:

- 10 1. The combination with a wrench head and wrench arm operatively connected therewith, of a handle-lever pivotally connected with said head in operative relation with said arm, there being a transverse bore in said handle-lever in registration with the operative end of said wrench arm; a sealed compressible metal chamber filled with fluid and having corrugated sides arranged in said bore and having threaded connection therewith; a contact cap loosely fitting over the 15 end of said chamber and in said bore and making operative contact with said wrench arm; and a pressure gauge in operative communication with said chamber.
- 15 2. The combination with a wrench head and wrench arm operatively connected therewith, of a handle-lever pivotally connected with said head in operative relation with said arm, there being a transverse bore in said handle-lever in registration with the operative end of said wrench 20 arm; a sealed compressible metal chamber filled

with fluid and having corrugated sides arranged in said bore and having threaded connection therewith; a contact cap loosely fitting over the end of said chamber and in said bore and making operative contact with said wrench arm; a 5 pressure gauge in operative communication with said chamber; and a controlling connection between said wrench arm and handle-lever permitting limited movement between them.

3. The combination with a wrench head and a 10 wrench arm member operatively connected therewith, of a handle lever member pivotally connected with said head in operative relation with said arm member, there being a transverse bore in one of said members; a sealed fluid filled 15 chamber threaded in said bore in operative contact with the other of said members; and a pressure gauge in operative communication with said chamber.

4. The combination with a wrench head and a 20 wrench arm member operatively connected therewith of a handle lever member pivotally connected with said head in operative relation with said arm member, there being a transverse bore in one of said members; a sealed fluid- 25 filled chamber having flexible sides removably mounted in said bore in operative contact with the other of said members; and a pressure gauge in operative communication with said member.

BEN PEPPERDINE. 30
